UNITED STATES PATENT OFFICE.

WILLIAM PATON THOMSON, OF NEW YORK, N. Y.

THRUST-EQUALIZING RAIL-PLATE.

1,298,827.

Specification of Letters Patent. Patented Apr. 1, 1919.

Application filed September 17, 1918. Serial No. 254,427.

To all whom it may concern:

Be it known that I, WILLIAM PATON THOMSON, citizen of the United States, residing at New York, in the county of New York and State of New York, have invented 5 certain new and useful Improvements in Thrust-Equalizing Rail-Plates, of which the following is a specification.

This invention relates to a novel and practical improvement in railway rail plates employed between the rail and ties of the roadbed, and has for its chief object the provision of a rail plate structure that will automatically adapt and adjust itself to a 10 natural and correct seating against a tilted rail base, and in and on the tie.

In the development of railway track equipment various expedients and forms of construction have been resorted to as a 20 means of protection for the fibers of the wood in the tie, and also to afford a more desirable and stable bearing for the rail base than is obtainable when the rail rests directly upon a wooden tie. These efforts 25 have included experimentation along the lines of modifying the form of a tie plate so as to establish a predetermined inclination for the rail, as distinguished from the more general practice of placing the rail 30 vertically on the tie. But, the practical difficulties in arbitrarily determining the correct degree of inclination for the rail as a basis from which to construct a tie plate is one of the problems that has confronted 35 engineers and manufacturers in making an acceptable design that would provide for a correct and proper seating of the tie plate with relation to the rail base and to the tie.

These and other conditions have led up to 40 the conception of the present invention which is founded on entirely new and different principles from those followed in prior practices. Accordingly, the invention primarily and essentially involves a principle 45 of construction which departs from the practice of establishing a definite degree of inclination for the rail in order to set the same in a theoretically proper relation to the wheel tread; it provides, on the contrary, a rail plate structure designed with such a disposition of tie-bearing surfaces as to permit the wheel load forces to act with sufficient freedom through the rail to make these forces the determining factors in such 55 a progressive embedment of the rail plate

in the top surface of the tie as to stabilize the rail plate thereon at whatever degree of inclination is representative of the operative relation between the acting and reacting forces of the road bed, the tie, the rail plate, the rail and the loaded wheels. Therefore, it will be apparent that it is proposed to so correlate the structural elements and forces as to automatically attain, in a much more practical and reliable way than 60 has hitherto been possible, the most efficient coöperation between the wheel tread and the running surface of the rail.

A further practical and important object of the invention is to provide a rail plate 70 with a novel tie bearing surface which will accommodate itself with facility to any of the usual irregularities in the top surface of the tie which may be produced by improper hewing or otherwise. It is this feature of 75 the invention that renders the rail plate of great adaptability and assures an automatic adjustment or rocking to an easy and true bearing against the under side of the rail base prior to the load forces coming into 80 play to give a final seating to the rail plate in accordance with the principles of the invention. In this connection it is important to note that a fundamental principle underlying the invention is that the tie bearing 85 surfaces of the rail plate shall be so disposed with reference to each other and to the rail bearing surface of the rail plate, that, as the embedment of the rail plate progresses, a preponderant area of rail 90 bearing surfaces of the tie plate operates to supplement the tendencies of the load forces to tilt the rail plate, and the rail superimposed upon it, into a final desirable position.

A further and more general object of the 95 invention is to provide a tie bearing or tie seating formation at the under side of the rail plate whereby the effect of the progressive embedment of the rail plate is to produce compression of the wood fibers of 100 the tie in decreasing ratios from a zone of maximum compressive resistance. Thus, as the compressive load force tends to embed the plate in the tie, new areas of wood fiber are successively brought under compression, until the ultimate bearing surface of the plate upon the tie extends throughout the width of the plate. And, by the time that the plate has a full bearing and final position 105 on the tie, the more densely compressed 110

portion of the tie will have been automatically situated to the best advantage to resist forces ordinarily tending to unseat a tie plate or cut the fiber of the wood at the edges of the plate. Hence, there will be little or no tendency for the present rail plate construction to sink into the tie at the edges of the plate, and consequently, in addition to the other advantages and objects set forth, the present type of rail plate secures a maximum degree of protection for the tie.

With the foregoing and other objects in view, which will more readily appear as the 15 nature of the invention is better understood, reference may be made to the accompanying drawings which illustrate typical embodiments of the invention and fully illustrate the various principles involved. In the 20 drawings:—

Figure 1 is a side edge view of a typical design of rail plate embodying the present invention, illustrating it in an initial unseated position and indicating the relation thereto of the rail, the car wheel, and the resultant of the applied forces.

Fig. 2 is a view of the same parts shown in Fig. 1, but illustrating the rail plate and rail tilted to a desirable coördinated working 30 relation, with the resultant of the applied forces substantially coinciding with the vertical axis of the rail.

Fig. 3 is a bottom plan view of the rail plate structure shown in Figs. 1 and 2.

Fig. 4 is a graphic illustration of a primary form of rail plate showing the principle of construction involved and elucidating the functioning thereof.

Fig. 5 is a detail edge elevation of another 40 modified form of the rail plate structure.

Fig. 6 is a bottom plan view of the plate shown in Fig. 5.

Fig. 7 is an edge elevation of a further modification.

Fig. 8 is a bottom plan view of the plate shown in Fig. 7.

Similar reference characters designate corresponding parts throughout the several figures of the drawings.

To illustrate the novel principles of construction, and functions, provided for in the present invention, reference is first made to a typical design shown in Fig. 1 of the drawings. In this typical drawing there is 50 shown a rail plate, designated generally as T, supporting thereon a rail R engaged by the tread of the wheel W in the usual well known manner. According to the invention the plate is constructed with a medial enlargement E preferably of such form and location that, under the influence of the grip of the rail and the wheel loads, the plate will automatically rock or adjust itself into such a position with reference to the upper 60 surface of the tie as to give the proper cant

or angle to the rail to thereby coördinate or balance the wheel and roadbed forces, acting and reacting through the rail, and so to produce a stable condition of the loaded rail because the unseating or up-setting forces 70 have been so balanced or neutralized. That is to say, instead of providing the rail plate with a rail supporting face of predetermined inclination to cant the rail, it is proposed to so construct the same as to enable the rail to 75 find its natural ultimate position through the action of the load forces which vary more or less in accordance with the conditions of track and road bed.

The medial enlargement E, and its unsymmetrical form, is a fundamental feature of the new rail plate structure, and in order to compel the desired action of the plate it is proposed to provide the said enlargement with suitable primary and secondary bearing faces so constructed and arranged as to produce somewhat the action of a pivot, causing the necessary plate movement to effect the proper seating of the rail under the stress of the imposed loads and forces. 80 Thus, it will be apparent that this medial portion E is of a relatively greater thickness or depth at one point than the balance thereof whereby sufficient clearance will be provided toward the edges of the plate to 85 permit the base to have a progressive embedment in the tie as it works to its final position.

Obviously, the provision of a body of metal of relatively greater depth at the proper point to provide the action above set forth may be carried out in various forms, but a typical construction such as shown in Fig. 1 may involve forming the bottom of 90 the rail plate of a substantially stepped formation with the maximum depth thereof located approximately beneath the vertical center of the web of the rail. This stepped formation of the under side of the rail plate therefore produces a medial enlargement or projection whose apex constitutes a primary bearing area or face 1, while the opposite sides thereof respectively are formed with separate series of longitudinal steps 2 and 3 95 which present a plurality of secondary bearing areas or faces 4 of varying degrees of resistance to embedment. It will also be noted from Fig. 1 that the general inclination or angle of the opposite series of longitudinal steps is preferably different; that is to say, the relative inclination of the series of steps 2 is preferably steeper than the relative inclination of the series of steps 3 with reference to the rail bearing surface of the plate, whereby as the rail plate embeds itself in the tie, a lesser resistance to this embedment will be offered by the series of steps having the steepest general inclination. Therefore, it 100 may be readily seen that the invention contemplates locating the medial enlargement 105 110 115 120 125 130

on the under side of the rail plate so that the same will present a maximum compressive resistance to the fibers of the tie at a point substantially between a plane $x-x$ intersecting the gage side of the rail head and parallel to the vertical center of the rail, and another plane $y-y$ parallel to $x-x$ and located preferably between the vertical center of the rail and the outer edge of the rail flange.

With the described formation at the under side of the rail plate it will be apparent that when the same is seated upon the tie the primary bearing area or face 1 will first come into play and seek an embedment, and subsequently the oppositely disposed secondary areas or faces 2 and 3 will come into action to compress the wood fibers of the tie in decreasing ratios, away from the zone of maximum compressive resistance, thus bringing new areas of wood fibers successively under compression until the ultimate bearing surface of the rail plate extends throughout the full width thereof.

Also, in the light of Fig. 1 and the principles herein discussed, it may be observed that the extent of the preponderant area of tie bearing surfaces, tending to supplement the load forces in tilting the plate, may be varied to any reasonable extent by varying the sequence and size of the secondary areas that are adapted to be progressively brought into contact with the tie.

The principle of construction underlying the invention is graphically shown in Fig. 4. From this illustration it will be obvious that the characteristic feature is that of the bluntly formed medial enlargement or projection of metal at the under side of the plate, formed at opposite sides of its apex with bearing areas, one of which offers a greater resistance to tie embedment than the other. These separate bearing areas may, as shown, consist of smooth inclined faces 2^a and 3^a set at different angles to the horizontal, so that one will be steeper and of less extent than the other, and will therefore offer less resistance to tie embedment so that the plate will settle first toward such steeper area in seeking its proper position with reference to the rail and the tie. This function may be controlled to any desired degree by forming the said inclined bearing areas with the series of steps α and β respectively, indicated by the dotted lines in Fig. 4. These steps may be provided in different sizes to meet different predetermined conditions, but, as indicated, the steps in the narrower and steeper bearing area are preferably of smaller size and less total area than the steps on the opposite tie bearing area, so as to offer a lesser resistance to tie embedment, as and for the purposes set forth. Therefore, it will be obvious that, as graphically illustrated in Fig. 4, the same result, substan-

tially may be attained by the use of either a stepped or a smooth conformation of the tie bearing face of the plate (or even a combination of both types of conformation), so long as the underlying principles herein set forth are observed.

The foregoing views of Figs 1 and 2 also illustrate that the greatest resistance to embedment of the rail plate in all forms thereof is located within a plane between the vertical center of the rail web and an edge of a rail flange, whereby under ordinary conditions the forces acting upon the gage side of the rail will also cause the inner or gage side of the rail plate to embed more quickly in the wood than the other side and thus so force the plate to assume its proper inclination with reference to the particular operative forces imposed thereon.

Another embodiment of the invention, involving all of the principles heretofore discussed, is shown in Figs. 5 and 6 of the drawings, wherein the underside of the rail plate T is provided with a series of juxtaposed and eccentrically related enlargements 6 and 7 of different area, the smaller enlargement constituting the primary tie bearing element and being located more or less centrally at the underside of the rail plate with reference to the upper rail bearing surface. This construction is simply another of many ways of producing the stepped formation at both sides of the point of maximum projection of the medial enlargement, whereby progressive embedment into a tie of yielding texture will take place in the manner previously described.

A still further embodiment of the invention is shown in Figs. 7 and 8 of the drawings wherein the under side of the plate is provided with a series of relatively few longitudinally extending steps, the lowermost one 8 of which constitutes a primary bearing face. The secondary bearing face preferably comprises a single step or shoulder 9 at one side of the primary bearing face, and a multiplicity of relatively smaller steps or shoulders 10 at the opposite side of said primary bearing face. These several steps or shoulders 10 are of greater total extent or area than the single step or shoulder 9 so as to offer greater resistance to tie embedment. Furthermore, in this form of the invention, shown in Figs. 7 and 8 of the drawings, the rail plate structure is provided at its underside with an intermediate projecting bearing area of maximum compressive resistance to the tie.

It will now be apparent that in all forms of embodiment the present invention involves what has been termed a bottom medial enlargement of an unsymmetrical and blunt form so as to provide at opposite sides of its apex or crown separate tie bearing areas, one of which presents greater progressive re-

sistance to the tie embedment than the other, and preferably the apex of this unsymmetrical enlargement or bulk of metal is offset to one side of the location of the vertical center of the rail to bring the progressively preponderant area of tie-bearing surfaces as nearly as practicable into a location where it will be intersected by the resultant of the wheel load and wheel thrust forces which usually passes through a rail flange. This will be apparent from the illustration of Fig. 1.

From the foregoing it will be appreciated that another desirable feature of the present invention is that of providing a rail plate structure wherein the load and strains are localized in such a manner that the structure lends itself readily to an economical and scientific distribution of metal, as compared with the ordinary heavy tie plate structures.

It will now also be appreciated that another important object achieved by the present invention is the correction of faults arising from the relatively limited bearing of the car wheels on the gage side of the rail head, with the rail and tie plate seated according to conventional practices. It will be apparent from Fig. 1 of the drawings, with the rail in a conventional upright position, that the wheel loads are focused on a relatively small bearing on the gage side of the rail head, and if this loading is maintained dangerous conditions may result such as the aggravation of incipient transverse fissures to a point where they actually become a menace. Therefore, it will now be clear that the load forces applied on the narrow area on one side of the rail head, reacting against the preponderant area of compressive resistance on the opposite side of the rail constitute a "couple" to compel the wheel, the rail, and the rail plate to assume such relations as will eliminate the couple. Consequently, in the carrying forward of the present invention it is anticipated that the automatic nature of this structure will be more effective than present practices, not only in supporting the rail in a canted position but that it will be conducive to a firmer and more lasting tie support; also a better distribution of wheel strains and bearings, such as will tend to reduce materially the injurious effects upon the structure of the rail head which are incident, first, to too great concentration of wheel bearing upon a narrow strip of the running surface of the rail head and, second to such a focusing of wheel loads on the gage side of the rail as to aggravate incipient transverse fissures to a point where they become dangerous.

Various changes in the form, proportion and minor details of construction may be resorted to without sacrificing any of the advantages of the invention and in that connection it will be observed that only certain

preferable forms of the invention have been selected for illustration showing the separate bearing areas of the medial enlargement as being inclined in substantially straight lines. However, it will be obvious that these areas may be struck on curved, or substantially curved lines, without departing from the intended purpose of the invention, so long as there is preserved the feature of a blunt bottom medial enlargement or projection of metal formed on opposite sides of its crown or apex, or point of greatest downward projection, with separate bearing areas which permit of a relative tilting or rocking movement of the plate as it automatically settles either one way or the other to a proper seating in the tie under the influence of the acting and reacting forces.

The term blunt as applied to the said medial enlargement is employed in the ordinary meaning of a flat, curved or pointed surface being non-piercing, dull or obtuse, as distinguished from a piercing, sharp or acute surface. That is, according to the present invention, the medial enlargement must be bluntly formed in order to make possible its functioning in the manner herein explained to attain the object desired.

I claim:

1. A rail plate provided with a medially crowned base adapted to have a lateral progressive seating engagement with the tie.
2. A rail plate provided with a base having means for compressing the wood fibers of the tie beneath the same in decreasing ratio away from a zone of maximum compression located entirely beneath the rail base.
3. A rail plate provided with a base having medial bluntly formed means for placing the fibers of the tie beneath the intermediate portion thereof under greater compression than toward the edges.
4. A rail plate having at the bottom a single crown located underneath the rail base, and opposed tie-bearing areas so separated by said crown as respectively to offer different resistance to tie embedment on opposite sides of the crown.
5. A rail plate having at the bottom a medial crown, and bearing areas separated by said crown and respectively disposed at different angles whereby one area offers a greater resistance to tie embedment than the other.
6. A rail plate having at the bottom a medial crown, and bearing areas separated by said crown and one of which has a steeper inclination than the other whereby it offers a lesser resistance to tie embedment.
7. A rail plate having at the bottom a medial crown, and bearing areas separated by said crown and one of which is narrower and of less extent than the other whereby it offers a lesser resistance to tie embedment.
8. A rail plate having at the bottom a me-

- 5 dial crown, and bearing areas separated by said crown and one of which is set at a relatively steep inclination and is of less total area than the other whereby it offers a lesser resistance to tie embedment.
9. A rail plate provided at the bottom with a bluntly formed medial enlargement having on opposite sides of its apex separate bearing areas for tie embedment.
10. 10. A rail plate provided at the bottom with a bluntly formed medial enlargement having on opposite sides of its apex separate tie bearing areas respectively disposed at different inclinations.
15. 11. A rail plate provided at the bottom with a bluntly formed medial enlargement having on opposite sides of its apex inclined bearing areas for tie embedment.
20. 12. A rail plate having at the bottom a medial enlargement formed on opposite sides of its apex or crown with separate bearing areas one of which has a steeper inclination than the other.
25. 13. A rail plate provided at the bottom with a medial enlargement or projection of metal formed on opposite sides of its apex or crown with separate bearing areas, one of which areas offers a greater resistance to tie embedment than the other.
30. 14. A rail plate having a base provided with a medial bluntly formed primary bearing face adapted to offer a greater compressive resistance to the tie than adjacent portions of the base of the plate at each side of the said primary bearing face.
35. 15. A rail plate having a base provided with a medial bluntly formed primary bearing, and secondary bearing areas separated by said primary bearing and divergently related thereto.
40. 16. A rail plate having at the bottom a primary tie bearing located underneath the rail base, and opposed secondary tie-bearing areas so separated by said primary bearing as respectively to offer different resistance to tie embedment on opposite sides of said primary bearing.
45. 17. A rail plate provided with a base having a primary portion adapted to have an initial engagement with the tie, and secondary bearing areas of different area respectively arranged in substantially divergent relation to the said primary portion.
50. 18. A rail plate having a base provided with a single bluntly formed tie bearing enlargement located between two planes which are perpendicular to and intersect the upper face of the rail plate, and one of which planes is adapted to intersect the gage side 60 of the head of a superposed rail and the other of which is adapted to intersect the opposite flange of said rail.
65. 19. A rail plate including a base having a plurality of tie bearing areas one of which is medially located at a greater depth below its rail bearing surface than are the remainder of said tie bearing areas.
20. A rail plate having a base provided with a thickened portion bulging to a greater depth below its rail bearing surface between the upright medial plane of the rail web and a parallel plane spaced at a distance to one side of said medial plane of the rail web, than it does at either side of the space between said planes. 70
21. A rail plate including a base having a plurality of thicknesses measured at right angles to its tie bearing surface, the average thickness being greater on one side of the portion of maximum thickness than on the other. 75
22. A rail plate provided with a base having a plurality of tie bearing areas, of which the average depth below its rail engaging surface is greater on one side of the tie bearing area of greatest depth than it is on the other. 80
23. A rail plate having a base provided with tie bearing surfaces so disposed in variably distant relation to its rail bearing surface that progressive embedment into a tie of yielding texture will, during the initial stages of the embedment, encounter a greater amount of the tie bearing surfaces of the plate on one side of a plane intersecting the central portion of the rail base than it will encounter on the opposite side of said plane. 90
24. A rail plate having a bluntly formed tie bearing constituting a pivotal means of initial engagement with the tie. 100
25. A rail plate having a base provided with an embedding enlargement which presents an initial tie engaging portion and opposite secondary tie engaging portions inclined thereto. 105
26. A rail plate having a base provided with an embedding enlargement which presents an initial tie engaging portion and opposite secondary tie engaging portions inclining thereto, the secondary tie-engaging portion toward one edge of the plate being of less area than the secondary tie-engaging portion toward the opposite edge of the plate. 110
27. A rail plate having at the bottom a single crown located underneath the rail base, and opposed stepped tie-bearing areas so separated by said crown as respectively to offer different resistance to tie embedment on opposite sides of the crown. 115
28. A rail plate provided at the bottom with a medial enlargement formed on opposite sides of its apex with separate bearing areas of stepped formation. 120
29. A rail plate provided at the bottom with a medial enlargement formed on opposite sides of its apex with separate bearing areas of stepped formation one of said areas being of less total extent than the other so 125
- 65 is medially located at a greater depth below 130

as to offer a lesser resistance to tie embed-
ment.

30. A rail plate having at the bottom a
medial enlargement provided at its apex or
5 crown with a primary bearing and on oppo-
site sides of the latter with separate stepped
bearing areas one of which areas offers a
greater resistance to tie embedment than
the other.

10 31. A rail plate having at the bottom a
medial crown and stepped bearing areas
separated by said crown and respectively
disposed at different angles whereby one
area offers a greater resistance to tie embed-
15 ment than the other.

32. A rail plate having at the bottom two
separate stepped bearing areas one of which
has a steeper inclination than the other
whereby it offers a lesser resistance to tie
20 embedment.

33. A rail plate having at the bottom two
separate stepped bearing areas one of which
is narrower and of less extent than the other

whereby it offers a lesser resistance to tie
embedment.

34. A rail plate having at the bottom two
separate stepped bearing areas one of which
is set at a relatively steep inclination and
is of less total area than the other whereby
it offers a lesser resistance to tie embedment. 30

35. A rail plate provided at the bottom
with a medial enlargement formed on oppo-
site sides of its apex with inclined stepped
bearing areas for tie embedment.

36. A rail plate provided at the bottom
with a medially located primary bearing
and secondary stepped bearing areas, the
steps of one of the secondary areas being of
less size and of less total area than the
steps of the other secondary area. 40

In testimony whereof I hereunto affix my
signature in the presence of two witnesses.

WILLIAM PATON THOMSON.
